UNITED STATES PATENT OFFICE

GUSTAV F. GERDTS, OF BREMEN, GERMANY

STEAM TRAP

Application filed April 6, 1929. Serial No. 353,154.

My invention relates to steam traps or devices for draining the condensate from pipe lines carrying steam under pressure, and its object is, to provide a reliable, continuously operating device of this character of comparatively small size and light weight containing only immovable operating parts, as such with a plurality of labyrinthic insulating ducts in which the condensate, in passing through without revaporization, is gradually reduced in pressure with scarcely any loss of heat, and in such a manner as to most successfully bar any escape of the steam.

I attain these improvements, for instance, by securely holding to a tapering plug in axial juxtaposition and contacting parallelism a number of impervious baffle plates and inserting the plug into a straightway shell or housing so that the plates are confined in the same. The baffle plates, in the form of thin disks being plain or ungrooved on one face and having a perforation near the periphery to admit the condensate comprise, on the other face, a substantially peripheral inlet and distributing chamber, a substantially central outlet and collecting chamber, a radial extension of the outlet chamber to connect with the inlet perforation of the adjacent plate, and a central perforation for the holding bolt.

The baffle plates, contacting with unlike faces and inlet perforations 180° apart, thus form between themselves two substantially semicircular sections or groups of labyrinthic channels arranged in parallel adapted to act as capillaries, whilst the labyrinths of all of the different baffle plates are in multiple series, constituting devious paths which being constantly filled with the water of condensation bar and entirely prevent any escape of the steam.

The baffle plates or steam retaining disks consist of an elastic material of low heat conductivity, whereby loss of heat is reduced to a possible minimum, revaporization of the condensate can not occur and an unrestricted flow of the condensate through the labyrinths is assured, whilst mud and grit are prevented from entering the ducts by a strainer but may settle in a chamber

provided for that purpose, to be discharged through a by pass controlled by a valve.

By reason of its reduced size and weight the new trap may be most conveniently inserted in the pipe line at any point within easy reach, like any ordinary straight-way valve, without having to be supported in any other way.

It requires only a few minutes time to take out, clean and replace the plug with the baffle plates and the strainer, the loosening of a single nut being sufficient to remove the plug which is forced to its seat by a hinged lever and a hinged bolt.

In describing my improvements reference is made to the accompanying drawings in which

Figure 1 is a section of the steam trap, partly in view.

Figure 2 shows a baffle plate in cross section through the middle.

Figure 2a is a view of the ungrooved face of a baffle plate.

Figure 2b is a view of the grooved face of a baffle plate.

Referring now to the drawings, *a* is the shell or housing with admission and discharge openings and also an intermediate opening to receive the tapering plug *b* with the holding bolt *c* integral therewith.

The baffle plates or steam retaining disks *d* are held against the inner face of the plug *b* by means of the bolt *c*, perforated end disk *e* and wing nut *f*, whilst the plug is provided with a circumferential passage *g* in direct communication with the discharge opening of the trap and also indirectly with the admission opening through passage *i* in the plug and the labyrinthic ducts of the baffle plates.

Each baffle plate has a perforation, as *l*, to admit the condensate from the end disk *e* or from the adjacent plate to the substantially peripheral distributing chamber *m*, a substantially central collecting chamber, as *n*, limitedly extending radially and diametrically opposite to perforation *l* to a point facing the inlet perforation of the following adjacent plate, the two chambers *m* and *n* being connected by the radial channels *o*, *o'*

and the interconnecting substantially concentric channels, as p , which form labyrinths on opposite sides.

5 A strainer, as q , prevents any mud and grit from entering passage j of the end disk e but causes the same to settle in the mud chamber r , to be discharged through valve s . A hinged lever, as t , holds the plug b to its seat by means of the hinged bolt u and 10 the nut v .

The condensate enters the distributing chamber m through the strainer r , the perforation j of the end disk e and the inlet perforation l of the plate, whence it passes 15 in numerous streams through the radial channels o, o' and the interconnecting concentric channels p into the central collecting chamber n and thence through the radially extending passage n' to the inlet perforation of the following adjacent plate or 20 to the passage i of the plug b .

The condensate, in passing from chamber m to chamber n has its pressure reduced mainly by reason of being divided into a 25 number of streams which impinge at the numerous intersections of the radial with the concentric ducts and thus make it impossible for the steam to penetrate the labyrinthic ducts.

30 The material employed to make the baffle-plates elastic and of low heat conductivity consists mainly in a mixture of asbestos, rubber, bakelite and an acid-resisting binding substance, the proportions of the different materials, and the pressure at which they are formed into thin, channeled plates to be such as to successfully resist not only the action of saturated but also that of highly super-heated and high pressure steam.

40 Having thus described my invention, what I claim as new, and desire to secure by Letters Patent, is—

1. In a steam trap having a shell with an admission, a discharge and an intermediate 45 opening, a plug held in the intermediate opening and forming with the shell a steam tight circumferential duct in direct communication with the discharge opening and communicating with the admission opening 50 through an axial passage leading to the inner face of the plug and through labyrinthic channels formed by and between a plurality of baffle plates immovably held against the said inner face of the plug in axial juxtaposition and contacting parallelism.

55 2. In a device of the character described having a shell with an admission, a discharge and an intermediate opening, the combination with a plug held in and closing the intermediate opening having a circumferential duct in direct communication with the discharge opening and communicating with the admission opening through 60 groups of labyrinthic channels formed by and between a number of centrally per-

forated baffle plates consisting of an elastic material of low heat conductivity, of a bolt integral with the plug to reach through the central perforations of the plates, a lever hinged to the shell, a bolt hinged to the shell, and a nut, whereby the plug is held to its seat. 70

3. In a device of the character described having a shell with an admission, a discharge and an intermediate opening, a plug held in and closing the intermediate opening, having a circumferential duct in direct communication with the discharge opening and communicating with the admission chamber through labyrinthic channels formed by and between a number of contacting baffle plates secured to the plug consisting of an elastic material of low heat conductivity with an inlet perforation near the periphery, the plates being ungrooved on one face and comprising on the other face a peripheral distributing chamber, a central collecting chamber, radial and interconnecting concentric channels to connect the two chambers, and a radial extension of the collecting chamber to communicate with the inlet perforation of the following adjacent plate. 80

4. In a steam trap having a shell with an admission, a discharge and an intermediate opening, a plug closing the intermediate opening and the inner face of which is provided with an axial passage in unobstructed communication with the discharge opening and communicating with the admission opening through labyrinthic channels formed by and between a plurality of baffle plates having square perforations in the center immovably held against the inner face of the plug in axial juxtaposition and contacting parallelism by means of a square bolt. 95

5. In a steam trap having a shell with an admission, a discharge and an intermediate opening, a plug closing the intermediate opening and the inner face of which is provided with an axial passage in unobstructed communication with the discharge opening and communicating with the admission opening through labyrinthic channels formed by and between a plurality of baffle plates held against the inner face of the plug, the grooves on one face of each baffle plate forming two semi-circular groups of labyrinthic channels on opposite sides arranged in parallel. 100

6. In a steam trap having a shell with an admission, a discharge and an intermediate opening, a plug closing the intermediate opening and from the inner face of which extends a passage in unobstructed communication with the discharge opening and communicating with the admission opening through labyrinthic channels formed by and between a plurality of baffle plates held 115 120 125 130

against the inner face of the plug with their dissimilar faces contacting and the perforation near the periphery of one plate being arranged 180° from that of the adjacent one.

5 In testimony whereof I have hereunto signed my name.

GUSTAV F. GERDTS.
